FIG. 1A.

FIG. 2A

UNITED STATES PATENT OFFICE.

ALFRED ERNEST HUDD, OF LIVERPOOL, ENGLAND, ASSIGNOR TO AUTOMATIC TELEPHONE MANUFACTURING COMPANY LIMITED, OF LIVERPOOL, ENGLAND.

RAILWAY SIGNALING SYSTEM.

Application filed January 4, 1921. Serial No. 434,927.

To all whom it may concern:

Be it known that ALFRED ERNEST HUDD, a subject of the King of Great Britain, residing at "Stoneleigh" Orient Drive, Gate 5 acre, Liverpool, England, has invented certain new and useful Improvements in Railway Signaling Systems, of which the following is a specification.

The present invention relates to improvements in and relating to railway signaling systems and has for its object a simplified arrangement of track signaling which can be readily applied to tracks of considerable length.

15 In all railway tracks, there is a considerable amount of electrical leakage between the rails, and consequently, if the block is very long and current is continuously applied thereto, a considerable loss is incurred; 20 and if batteries are used to give a direct current supply, these rapidly become exhausted.

According to the present invention, signals or like devices controlling passage of the trains are in turn controlled by means of 25 momentary currents transmitted through the track. Preferably, the momentary current transmitted through the track is adapted to set in action a local track circuit, which is adapted to control the signal or other 30 apparatus.

The invention will be better understood by referring to the accompanying drawings, in which Figures 1 and 1^A show the application of the invention to a double track system while Figures 2 and 2^A show the application of the invention to a single track system.

It will be understood that these arrangements are only shown by way of example, as 40 considerable modifications may be made therein without departing from the spirit of the invention, when applied to other operating conditions. For instance, the signals are all described as being of the two position type which indicate danger when horizontal and clear when lowered to an angle of 45° pointing downward, altho, obviously, other signals could be employed without departing from the spirit of the invention.

50 Referring to Figures 1 and 1^A two stations

A and B are shown and the apparatus for one direction of train movement only is shown, that is to say, for trains moving in the direction from B to A on the lower track 1. The main track between A and B 55 is formed into a section by the insulators 2 and 3, while at station B, a short length of the lower track is insulated from the main portion by the insulator 4.

The invention will be better understood 60 by describing the operation of the system. Assuming that the signal man at station B desires the signal man at station A to accept a train. To do this, he operates his tapper key 5, sending positive current from earth

65 E, battery 6, back contact of armature 7 of local track relay 8, operating contact of tapper key 5, line 9, (which is an independent line running between stations A and B and is used solely for the purpose of intercommunication between the signal boxes but has no control whatever over the actual operation of the signals), resting contact of tapper key 10 at station A, bell 11, indicator 12 to earth. In this circuit, the bell 11 rings.

70 75 while the indicator 12 which is polarized does not operate with current in this direction, then the signal man at station A, to accept the train, presses the push button 13 thereby closing the following circuit over 80 the track. Negative pole of battery 14, lower rail of track 1, switch 15 controlled by the starting signal lever, track relay 16, upper rail of track 1, push-button 13 in operated position to positive side of battery 14.

85 The operation of relay 16 then depends upon whether there is a train or otherwise on the main portion of the track between A and B, if there is a train, the relay 16 will be short circuited and will not operate, whereas, if 90 there is no train or similar obstacle, the relay 16 will obtain enough current to energize and cause its armature 17 to make contact with the front contact. The closure of this contact, then connects battery 19 between 95 the locally insulated portion 18 of the lower rail of the track 1 and the upper rail. Then if the local track is clear of either train or obstruction, a circuit would be closed for the local track relay 8 in series with the 100

springs 20 of a release key 21 which is provided for a purpose to be explained later. The relay 8 operates and at its armature 22, locks itself on the local track circuit; consequently the signal transmitted over the line may be only transitory and the relay 16 only momentarily energizes. At its armature 23, the line indicator 24 is connected in series with battery 25, so that the line indicator 10 attracts its armature to show "train accepted". At armature 26, a circuit is prepared for the signal reverser 27; the signal reverser, which is essentially an electromagnetic clutch for connecting the chain 15 controlled by the signal lever with the signal proper, may be of any known type. The circuit for the reverser 27 is completed by the signalman pressing the push-button 100 and then operating the signal lever, which 20 causes the signal to be lowered; subsequently the circuit of the signal reverser is closed independently of the push 100 through the starting signal lever contacts 29. At armature 7, negative battery 30 is connected to 25 the operative contact of tapper key 5, so that when the signal man at B operates his tapper key to signify that he has received the acceptance signal, negative current is transmitted over the line 9. This causes the 30 bell 11 to operate as before and also the polarized indicator 12 which attracts its armature to show "train accepted". At the same time, the signalman at B lowers the signal to accept the train.

35 The train, on entering the first part of the track, short circuits the upper rail and the insulated portion 18 of the lower rail, whereby the relay 8 de-energizes and the circuits made by armatures 22, 23, 26 and 7 40 are again broken. The de-energization of the signal reverser 27, causes the signal to return to "danger", the de-energization of the line indicator 24, causes the armature to fall back against the mechanical latch 31, 45 thereby showing "train on line". The release of the armature 22 opens the locking circuit of the relay 8 so that this cannot again pick up until the relay 16 has been operated, which cannot take place until the 50 train has passed A and B; when this occurs, the signalman at A presses the push button 32 to operate the mechanical latch 33 whereby the armature of the indicator 12 is allowed to fall against the stop 35 to its 55 normal position to show "line closed". At the same time, the signalman operates his bell tapper key 10 and sends a code of rings to the signalman at B to ring his bell 36, the current being without effect on his line 60 indicator 37 in this direction. The signalman at B then presses his push-button 38 to operate the mechanical latch 31 to allow his indicator 24 to return to the normal position and also shows "line closed".

65 It will thus be appreciated, that by means

of the present invention, it is possible to provide with an equal degree of safety, a railway signaling system for long lines of track without necessitating a very large expenditure of current, it being impossible to 70 lower the signal if there is a train on the section A to B.

It might happen that accidentally, the signalman at A had sent the "accept" signal to B when it was not required and for that 75 reason, the release key 21 is provided, so that the circuit of the local track relay 8 may be broken at will. The contacts 15 and 29 on the starting signal levers are represented conventionally with the position of the signal, for instance, contact 15 is closed when the signal is at "danger" and is open when the signal is at "clear", while the contact 29 is open when the signal is at "danger" and is closed when the signal 85 is at "clear".

It will be understood that the apparatus shown in this figure, only represents that required for one direction of train movement between A and B, only one line 9 however 90 will be required for both directions of train movement, otherwise, with the exception of the bells 11 and 36 and the line indicators 12 and 37, the apparatus shown at A will be also provided at B for the other direction 95 of working and vice versa. This will be readily understood and need only be mentioned.

Referring to Figures 2 and 2A, the example is shown of the application of the invention to single line working between stations A and B. The track in this case is sub-divided a number of times as follows, considering the section as beginning from A:—To the right of the insulators 40 is 100 the local track circuit 41 covering the fouling points, this extends to the insulator blocks 42. To the right of the insulators 42 is a short stretch of local track 43, while to the right of the insulators 44, the main track proper 45 begins; this extends to the insulators 46 after which comes another short stretch of local track 47 similar to the track 43 and then to the right of the insulators 48 is a short stretch of local track 110 49 covering the fouling points, the insulation of the section occurring at 50. The tracks 41 and 49 suitably divided as shown by insulators 101, 102, 103 and 104, are protected by means of the track relays 51 and 52 permanently supplied with current from batteries 53 and 54, respectively, except when a train is passing over the sections as will be understood, the operation 115 will be better understood by referring to the 120 following description.

It will be assumed that the signalman at B has a train which he wishes to admit into the section B. He thereupon operates his tapper key 55, thereby closing a circuit from 130

earth; battery 56, armature 82, operated contact of tapper key 55, line 87, resting contact of tapper key 57, bell 58, indicator 59 to earth. The bell 58 rings but the line 5 indicator 59 does not operate with current flowing in this direction. The signalman then understands that B wishes the acceptance of the train, and to effect this, he operates the accepting lever 60 thereby closing 10 the following circuit. Positive pole of battery 65, "accepting" lever 60 in the operated position, upper rail of track 45, accepting lever 61 in its resting position, track relay 62, lower rail of track 45 and armatures 15 63 and 64 and their resting contacts to negative pole of battery 65. Then, if there is no train or obstruction on the track 45, the relay 62 will pick up and at its armature 66 connect battery 67 across the local track 47, so that if this track is free the local track 20 relay 68 will pick up and at armature 69 lock itself to the battery 67 through the local track, so that the restoration of the accepting lever 60 to its normal position, and the 25 consequent de-energization of the relay 62 will be without effect. At armature 70, of relay 68 a circuit is also closed for the battery 71, through a number of parallel paths. Firstly, the circuit of the signal reverser 72, 30 which is of similar construction to reverser 27, is operated, so that the signal may be lowered. Secondly, the circuit of the lever lock 73 of the signal Y will be prepared so that on the signalman operating the contact 35 maker on the signal lever, the signal may be lowered. Thirdly, the line indicator 74 will energize, thereby causing the indicator to show "train accepted." Fourthly, the permissive relay 75 will be operated which at 40 its armature 76 closes a locking circuit for itself, while at its armature 77 prepares a circuit for the lever lock 78 of the permissive calling on arm Z, while at armature 79 the circuit of the battery 80 is broken thereby, preventing a signal being accepted in the 45 opposite direction. This circuit has already been broken at armature 81 of relay 68, but this relay only governs a single train, while the relay 75 permits other trains to follow 50 in the same direction, and consequently is energized for a longer period. Relay 68 at armature 82 connects positive pole of battery 83 to the resting contact of tapper key 55. Consequently, when the signalman at B operates his tapper key to signify that he has 55 received notification of the acceptance of a train and has lowered the signal Y, positive current is transmitted over the circuit, battery 83, working contact of armature 82, operated contact of tapper key 55, resting contact of tapper key 57, bell 58, line indicator 59 to earth. The bell 58 rings and the line indicator 59 with this current, operates and attracts its armature, thereby showing 60 "train accepted." Consequently, a train enters the section. On entering the track 49 in the region of the fouling points, the relay 52 is de-energized and at its armatures 84 and 85, breaks the circuit of the lever 70 lock 73 and 78 of the signals Y and Z respectively, thereby preventing these signals being again lowered. On the train entering the section 47, the relay 68 de-energizes and at armature 69, breaks its locking circuit, 75 so that this can only be reset by the transmission of a fresh transient signal over the track 45, after the train has passed there-through. At armature 70 of relay 68 the signal reverser 72 is deenergized and the signal Y restores to "danger" position, at 80 armature 81 the circuit connection of the "accepting" lever and the battery 80 is restored but cannot be completed while the armature 79 is open, at armature 82 negative battery is restored to the lower contact 85 of tapper key 55. On the train entering the section and the line indicator 74 de-energizing, so as to show "train on line," the signal man at B operates his tapper key 55 thereby transmitting negative current over the line 87 which causes the indicator 59 to de-energize, thereby also showing "train on line." It should be understood that indicator 59 is polarized and can only be de-energized on a reversal of current through 90 its winding while indicator 74 de-energizes immediately on reversal of current.

Now it may be desirable to permit other trains to enter the section running in the same direction, and this may be effected as 100 will be described, by means of the permissive relay 75 and the permissive calling on arm Z. After the train has left the track 49 the relay 52 again picks up and at its armature 85 prepares a circuit for the lever lock 78 of the permissive signal Z. It will 105 be understood, that this circuit is completed through the armature 77 of the permissive relay 75 which relay is locked operated as previously described. Consequently, the signal man at B may continue to pass trains through one after another and as long as relay 75 is energized it is impossible for him to accept a train in the opposite direction. If however, it is desired to change the direction of running of the trains, then the signal man at B must operate his release button 86 thus breaking the 110 circuit of the permissive relay 75 which in turn opens the circuit of the lever lock 78 of the permissive signal Z at armature 77, and also its own locking circuit at armature 76. The signalman at B may then press his push button 88 and restore his line indicator to normal showing "line closed" and he may signal on his tapper key 55 to the signalman at A to do the same. He is then in a position to accept trains 115 in the opposite direction when the cycle of operations will be repeated as previously 120

125

130

described. It will be appreciated that by means of the invention, it is impossible for trains to be accepted in opposite directions of running on a single track, due to the 5 interlocking of the electrical circuits. At the same time, it should be understood that considerable modifications may be made in the manner of carrying out the invention without departing from the underlying 10 principles.

What I claim as my invention is:

1. A railway signaling system comprising a pair of insulated track rails, a source of electrical energy, switching means for 15 momentarily connecting said source of electrical energy in series with said rails, a device for controlling the passage of a train, electromagnetic means responsive to current transmitted over said rails for bringing said 20 device to its operative position, locking means for maintaining said device in its operative position independently of said electro-magnetic means, and means controlled by the passage of a train for rendering said locking means inoperative and permitting said device to restore to its normal position.

2. A railway signaling system, comprising a pair of insulated track rails, a source 30 of electrical energy, a manually-operated switch for momentarily connecting said source of electrical energy in series with said rails, a device for controlling the passage of a train, electromagnetic means associated 35 with said rails and responsive to the manual operation of said switch for bringing said device to its operative position, locking means for maintaining said device in its operative position independently of said 40 electromagnetic means, and means controlled by the passage of a train for rendering said locking means inoperative and permitting said device to restore to its normal position.

45 3. A railway signaling system comprising a pair of insulated track rails, a source of electrical energy, switching means for momentarily connecting said source of electrical energy in series with said rails, an electric relay for controlling the passage of a train, electromagnetic means responsive to current transmitted over said rails for bringing said relay to its operative position, locking means for maintaining said relay 50 in its operative position independently of said electro-magnetic means, and means controlled by the passage of a train for rendering said locking means inoperative and permit said device to restore to its normal 55 position.

60 4. A railway signaling system comprising a pair of insulated track rails, a source of electrical energy, switching means for momentary connecting said source of energy 65 in series with said rails, a signal, a device

for controlling the operation of said signal, electromagnetic means responsive to the current transmitted over said rails for allowing the movement of said signal to the clear position, locking means for maintaining said signal in its clear position independently of said electromagnetic means, and means controlled by the passage of a train for rendering said locking means inoperative and permitting said signal to restore to the danger 70 position.

5. A railway signaling system comprising a pair of insulated track rails, a source of electrical energy, switching means for momentarily connecting said source of electrical energy in series with said rails, a device for controlling the passage of a train, an electric relay responsive to current transmitted over said rails for bringing said device to its operative position, locking means for maintaining said device in its operative position independently of said relay, and means controlled by the passage of a train for rendering said locking means inoperative and permitting said device to restore to its normal 80 position.

6. A railway signaling system comprising a pair of insulated track rails, a source of electrical energy, switching means for momentarily connecting said source of electrical energy in series with said rails, an electromagnetic device for controlling the passage of a train, electromagnetic means responsive to current transmitted over said rails for bringing said device to its operative position, a holding circuit for maintaining said device in its operative position independently of said electromagnetic means, and means controlled by the passage of a train for rendering said holding circuit inoperative and permitting said device to restore to the normal position.

7. A railway signaling system comprising a pair of insulated track rails, a source of electrical energy, an electromagnetic relay connected to said track rails, switching means for connecting said source of energy to said rails to cause the energization of said relay, and a contact device controlled by said relay to complete a holding circuit for said relay independent of said switching means.

8. A railway signaling system comprising a pair of insulated track rails, a source of electrical energy, an electromagnetic relay connected to said rails, a second relay for connecting said source of energy to said rails to cause the energization of said first relay, and a contact device controlled by said first relay to complete a holding circuit independent of said second relay.

9. A railway signaling system comprising a short pair of insulated track rails, a source of electrical energy, an electromagnetic relay connected to said rails, a second pair of in-

sulated track rails of considerable length, a second electromagnetic relay connected to said second track rails and adapted to be momentarily energized thereover to connect 5 said source of electrical energy to said first-mentioned rails to cause the energization of said first-mentioned relay, and contacts controlled by said first relay to complete a holding circuit independent of said switch- 10 ing means.

10. A railway signaling system comprising a short insulated track rail, a second insulated track rail forming an extension of said first-mentioned track rail but of considerably greater length, and a third track rail forming the complement of the two first-mentioned track rails, a relay normally connected between said first rail and said third rail, a second relay connected between said 15 second rail and said third rail, a source of electrical energy, means for connecting said source of electrical energy between said second rail and said third rail for causing the energization of said second relay, a second 20 source of electrical energy, a contact device controlled by said second relay for connecting said second source of electrical energy between said first and said third rail to cause the energization of said first relay, 25 and a contact device controlled by said first relay to complete a holding circuit for said relay over the circuit including said first and said third mentioned rails.

11. A railway signaling system comprising a pair of insulated track rails, a source of electrical energy, an electromagnetic relay connected to said track rails, switching means for connecting said source of energy to said rails to cause the energization of said 30 relay, a contact device controlled by said relay to complete a holding circuit for said relay independent of said switching means, a signal, means for operating said signal, and a second contact device controlled by 35 said relay for rendering said signal controlling means effective in bringing the signal to its off-normal position.

12. A railway signaling system comprising a pair of insulated track rails, two sources of electrical energy, switching means located at each end of said track rails for momentarily connecting the corresponding source of electrical energy in series with said rails, devices for controlling the passage 40 of a train in either direction located one at each end of said insulated track rails, electromagnetic means responsive to currents transmitted over said rails for bringing the corresponding device to its operating 45 position, locking means for maintaining said devices in their operative position independently of said electromagnetic means, means controlled by the passage of a train for rendering said locking means inoperative and permitting said devices to restore 50

to their normal positions, and auxiliary contact devices controlled when a switching means is operated to disconnect the corresponding set of electromagnetic means.

13. A railway signaling system comprising a pair of insulated track rails, a source of electrical energy, switching means for connecting said source of electrical energy in series with said rails, electromagnetic means responsive to current transmitted over said 70 rails, a signaling circuit, other switching means controlled by said electromagnetic means for changing the nature of current transmitted over said signaling circuit.

14. A railway signaling system comprising a pair of insulated track rails, a source of electrical energy, switching means for connecting said source of electrical energy in series with said rails, a device for controlling the passage of a train, electromagnetic means responsive to current transmitted over said rails for bringing said device to its operative position, locking means for maintaining said device in its operative position, means controlled by the passage of a train for rendering said locking means inoperative and permitting said device to restore to its normal position, a signaling circuit, two auxiliary sources of electrical energy, and switching means controlled by said device for connecting either one or the other of said sources of electrical energy in the signaling circuit. 95

15. A railway signaling system comprising a main insulated track and two local track circuits located at each end of said main track, electromagnetic means and switching means located at each end of said main track, interconnecting means between said switching means and said electromagnetic means whereby the operation of a switching means renders the corresponding electromagnetic means inoperative, contact devices controlled by said electromagnetic means for energizing said local track circuits, and signaling devices controlled by 100 said local track circuits. 105

16. A railway signaling system comprising a main insulated track and two local track circuits located at each end of said main track, electromagnetic means and switching means located at each end of said main track, and interlocking circuits controlled by said local track circuits when operative to prevent the transmission of signaling currents over said main track. 110

17. A railway signaling system comprising a main insulated track and two local track circuits located at each end of said main track, electromagnetic means and switching means located at each end of said main track, interconnecting means between said switching means and said electromagnetic means, whereby the operation of a switching means renders the corresponding electromagnetic means inoperative, contact 115 120 125 130

devices controlled by said electromagnetic means for energizing said local track circuits, signaling devices controlled by said local track, an auxiliary device operated when one of said track circuits is energized, and a second signaling device controlled by said auxiliary device to permit the passage of successive trains in the same direction

after said energized track circuit has been de-energized on the passage of a train. 10

In testimony whereof I affix my signature in presence of two witnesses.

ALFRED ERNEST HUDD.
